UNITED STATES PATENT OFFICE.

JOHN A. SANQUIST, OF NEW WINDSOR, ILLINOIS.

SOCKET FOR CONCRETE BUILDING CONSTRUCTIONS.

1,091,168.

Specification of Letters Patent. Patented Mar. 24, 1914.

Application filed October 22, 1913. Serial No. 796,634.

To all whom it may concern:

Be it known that I, JOHN A. SANQUIST, a citizen of the United States, residing at New Windsor, in the county of Mercer and State 5 of Illinois, have invented certain new and useful Improvements in Sockets for Concrete Building Constructions, of which the following is a specification.

This invention relates to concrete building structures, and more particularly a socket member for supporting a stud, post or similar member from the floor of the building.

The invention is designed more particularly for use in connection with corn cribs and similar structures having concrete floors, although it is not limited to such use and may readily be employed in connection with other building structures.

It is the object of the invention to provide a socket member of novel construction which can be firmly embedded in the floor of the crib or other structure, and which will provide a strong and rigid support for the stud, post or similar member.

In order that the invention may be better understood, reference is had to the accompanying drawing, in which—

Figure 1 is a sectional view of a fragment of a floor showing the application of the invention; Fig. 2 is a vertical section on the line 2—2 of Fig. 1; Fig. 3 is a perspective view of the socket member; Fig. 4 is a cross section on the line 4—4 of Fig. 3; and Figs. 5 and 6 are plan views showing modifications.

Referring specifically to the drawing, the socket member is a casting or other form of metal shaped to produce a rectangular body portion 5 to receive the stud, post or similar upright member 6 to be supported. The socket member may have any other shape to correspond to the cross section of the upright member. The socket member 45 has an outstanding flange 7 projecting from its sides and extending entirely around the member, said flange being located intermediate the top and bottom thereof. From one side of the member projects a hook 8 having a shank 9 which is channeled or V-shaped in cross section, as clearly shown in Fig. 4, the channel being at the bottom.

Fig. 1 shows how the socket member 5 is employed. Two of such members are

shown embedded in the concrete floor 10 and tied together by a wire or other tie-member 11 made fast to the hooks 8 of the respective socket members. In placing the socket members, two of such are located opposite each other with their hooks pointing toward each other, and the tie-member 11 is then applied, whereby the two socket members are firmly held against spreading. The concrete material forming the floor 10 is filled in around the socket members flush with the top thereof, which embeds the parts 7, 8 and 9 as well as the tie-member 11 in said material. The flange 7 effectually prevents vertical displacement of the socket member, and the channeled part 9, which is filled with concrete, also resists any tendency toward tilting or lateral displacement, and the socket member is thus firmly embedded and anchored in the floor.

Fig. 5 shows a socket member 12 designed to hold a corner post, said member having two parts which are arranged at a right angle to each other, and from each of said parts a shank 13 extends having means for attaching a tie-member 14 which connects the angle socket member with an intermediate member 15, said intermediate member having shanks 16 projecting from opposite ends for attachment of the tie-members.

Fig. 6 shows another form of socket member 17 for a corner, this member, however, being rectangular and in all respects similar to the member shown in Figs. 1 to 4 with the exception that it has two projecting shanks 18 for attachment of tie-members 19 which connect with intermediate socket members 20.

I claim:

A socket member of the character described comprising a body portion having tie-rod anchoring means projecting from one side thereof, said means comprising a horizontal member which is channeled in cross section, the channel being at the bottom, and said member having its extremity provided with means for attachment of a tie-rod.

In testimony whereof I affix my signature in presence of two witnesses.

JOHN A. SANQUIST.
